UNITED STATES PATENT OFFICE.

JOHN PAUL HASS, OF GORHAM, NEW HAMPSHIRE.

AUTOMATIC TAKE-UP.

No. 834,472.

Specification of Letters Patent.

Patented Oct. 30, 1906.

Application filed September 12, 1905. Serial No. 278,164.

To all whom it may concern:

Be it known that I, JOHN PAUL HASS, a citizen of the United States, residing at Gorham, in the county of Coos and State of New Hampshire, have invented a new and useful 5 Automatic Take-Up, of which the following is a specification.

This invention relates to automatic take-ups, and has for an object to provide a device 10 of the class embodying new and improved features of utility, accuracy, simplicity, and efficiency.

A further object of the invention is to provide a device embodying improved means for 15 automatically taking up and compensating for changes in length of endless belts and the like.

A further object of the invention is to provide a device for association with a paper- 20 making machine and embodying means for automatically compensating for changes in the length of the felt and to maintain the felt at all times in a level position and accurately straight.

25 With these and other objects in view the present invention consists in the combination and arrangement of parts, as will be hereinafter fully described, shown in the accompanying drawings, and particularly pointed 30 out in the appended claims.

In the drawings, Figure 1 is a top plan view of the improved take-up associated with the felt of a paper-making machine. Fig. 2 is a longitudinal sectional view of a portion 35 of the frame of a conventional paper-making machine with the take-up applied and taken on line 2 2 of Fig. 1. Fig. 3 is a transverse sectional view taken on line 3 3 of Fig. 2 and showing one of the bearing-blocks in elevation.

40 Like characters of reference indicate corresponding parts in all of the figures of the drawings.

The automatic take-up forming the subject-matter of this application is adapted for 45 use in association with any form of endless belt, rope-drive, or endless apron. The invention is especially, although not exclusively, adapted for use in connection with the 50 felt of a paper-making machine and is here illustrated in connection with a conventionalized paper-making machine, having the base 10, upper frame-pieces 11, and felt 12. Upon the frame in any convenient positions 55 are erected the uprights 13, with their upper ends bifurcated to form the ears 14.

In the ears 14 are journaled the shafts 15 and 16, extending transversely of the machine and parallel with each other. Upon the shafts 15 and 16 are mounted the sprockets 17 and 18, over alined pairs of which pass the chains 19 and 20. The sprockets 18 must be rigid upon the shaft 16, and the sprockets 17 may be either rigid or loose upon the shaft 15. 60

Between the uprights 13 are secured the guides 21 21' and 22 22', extending longitudinally of the machine, and thereon are slidably mounted the bearing-blocks 23 and 24. Between and in the bearing-blocks 23 and 24 70 is journaled the roller 25, over which passes the felt 12. The ends of the chains 19 and 20 are secured, respectively, to the bearing-blocks, 23 and 24, as by the eyes 26 and 27, so that the blocks 23 and 24 and the opposite ends of 75 the roller 25 move simultaneously and in unison.

Upon the end of the shaft 16 is mounted the drum 28, about which is mounted the cable 29, from which is suspended the variable weight 30. 80

The drum 28 is rotatable upon the shaft 16, being held from displacement in any approved manner, as by the pin 31, and is provided with one or more spring-pressed pawls 32, engaging a ratchet-wheel 33, rigidly mounted upon the shaft. 85

It will be obvious that the weight 30 tends to move the sprockets 17 and 18 in the direction indicated by the arrow, which tend to 90 move the chain and bearing-blocks as indicated, thereby holding the felt taut at all times, but compensating for any variation in its length.

It will also be obvious that as the belt or 95 felt 12 becomes permanently lengthened the cable may be wound upon the drum by rotating the drum relative to the shaft 16 and about the ratchet-wheel 33.

It will be noted that the belt 12 remains 100 constantly in the same plane throughout its adjustment.

Having thus described the invention, what is claimed is—

1. A take-up device comprising a frame, 105 guides mounted upon the frame, bearing-blocks slidably mounted upon the guides and movable longitudinally of the frame, shafts mounted transversely of the frame, sprockets mounted upon the shafts, chains passing over the sprockets and with their ends secured to 110 the blocks, a roller journaled in the blocks, a

belt passing thereover, a drum mounted upon one of the shafts, a cable wound about the drum, a weight attached to the cable and tending to move the blocks longitudinally of the guides and to hold the belt taut.

2. The combination in a paper-machine of spaced uprights, guides mounted between the uprights and longitudinally of the machine, parallel shafts journaled in the uprights and extending transversely of the machine, alined sprockets mounted adjacent the ends of the shafts and above the guides, bearing-blocks slidably mounted upon the guides and movable longitudinally of the machine, a roller journaled in the blocks and extending transversely of the machine, an endless felt passing over the roller, chains passing over the sprockets and with their ends secured to the blocks and whereby the blocks will move simultaneously and equally, a drum mounted upon one shaft, a cable wound about the drum and a weight suspended upon the cable

and arranged to move the blocks to hold the felt taut.

3. A take-up device comprising a frame, guides mounted thereon, bearings slidably mounted upon the guides and movable longitudinally of the frame, a roller carried by the bearings, flexible devices extending above the bearings and each connected at its ends to opposite faces of one of the bearings, a drum movable with said flexible devices, a belt extending over the roller, and means for automatically rotating the drum to move the flexible devices and bearings to hold the belt taut.

In testimony that I claim the foregoing as my own I have hereto affixed my signature in the presence of two witnesses.

JOHN PAUL HASS.
